UNITED STATES PATENT OFFICE.

JOHN T. WILKIN, OF CONNERSVILLE, INDIANA, ASSIGNOR TO THE CONNERSVILLE BLOWER COMPANY, OF CONNERSVILLE, INDIANA, A CORPORATION OF INDIANA.

HIGH-SPEED LOBED-IMPELLER BLOWER.

Substitute for application Serial No. 101,903, filed April 14, 1926. This application filed March 2, 1927.
Serial No. 171,913.

In that type of rotary gas pumps and blowers primarily designed for increasing or decreasing gaseous pressures, and wherein the fluid flow is caused by the action of two interdigitated rotary lobed impellers arranged within a casing, the two impeller elements have mating surfaces of such a character as to form gas forwarding pockets between the impellers and the casing and also to maintain minimum and uniform clearance between the impellers themselves and between each impeller and the casing. Such impellers do not coact for relative rotation but are rotatively connected by intermeshing timing gears which also serve to transmit power from one impeller shaft to the other.

For convenience of description I shall designate such a structure as a blower, whether it be designed or used as a blower or gas pump, because the coaction of the several elements is the same in either case.

In the early period of development of blowers of this type their use was largely limited to the blowing of foundry cupolas, smelting furnaces, forge fires and the operation of cash carrying tubes for store service work; also for gas exhausters in gas works, all of which uses required pressure differences rarely exceeding one or two pounds per square inch. The demand for structures of this type has gradually increased until now they are used for many purposes which require pressure differences as high as fifteen pounds. For convenience of description I shall use the term "low pressure" for pressure differences below two and a half pounds, and the term "high pressure" for pressure differences between two and a half and fifteen pounds.

Heretofore in the manufacture of blowers of this type it has been the practice to make the lobes of the impellers hollow and as light as is consistent with necessary rigidity. I have found by long experience with blowers of this type having light impellers, each with two hollow lobes, that where the driving power is applied to one shaft, and the other impeller is driven through the gears, the wear on the teeth of the gears is

not uniform in all parts of the revolution, but is concentrated on a few teeth at two opposite portions of the revolution.

It has long been known, in the operation of blowers of this type, where each impeller has two lobes, that there is, twice in each revolution of each impeller, a cyclic variation of resistance to forward movement, because the travel of the point of contact between the impellers produces varying unbalanced areas of the impellers exposed to the pressure against which the blower is operated, the cycle of one impeller being spaced ninety degrees from the cycle of the other impeller.

It has also been known that with machines as heretofore built, there is a corresponding cyclic angular distortion or twist of each shaft between the connecting gears and the impellers, and that this distortion or twist permits a change in the angular relation of the impellers to each other. The amount of this angular distortion increases directly with the increase of the unbalanced area of each impeller and the pressure acting thereon. Theoretically the mating surfaces of the impellers should just avoid contact, and the actual clearances between such mating surfaces should, of course, be made as small as possible in order to decrease slippage or leakage of the gas from the high pressure side to the low pressure side between the mating lines of the two impellers.

In blowers of this type the highly fluctuating torque and unavoided inaccuracies of gears have necessitated excessive clearances between the impellers, and have limited the practicable speed to a pitch line velocity of approximately 700 feet per minute in small machines and approximately 1400 feet per minute in large machines, more or less depending on workmanship, materials, etc., because when higher speeds were attempted there would be a noisy and destructive action of the gears and impellers unless further and more excessive clearances were provided.

I have found that the destructive noisy action at speeds heretofore found to be impracticable is the result of a failure to

maintain continuous contact of the working faces of the gear teeth, and that this failure is caused, first by the variable torque which is exerted upon the impellers by the fluctuating gas pressures within the machine, acting on the varying unbalanced areas of the impellers, thereby producing fluctuating torsional deflections of the shafts between the impellers and their gears, increasing as pressure increases, and second, by an incorrect formation and spacing of the gear teeth due to inaccuracies of commercial production, which give fluctuating impulses to the driven gear, such impulses, as is well-known, increasing in intensity as the square of the increased speed.

I have also found that, in such blowers this destructive and noisy action increases as the gears become worn, because, as previously stated, the wear of the gear teeth, when light impellers are used, is not uniform throughout the circumference but is concentrated on a few teeth at two opposite portions of the gear. It is, therefore, evident that this uneven wear of the gears would tend to transmit to the driven impeller additional cyclic impulses.

One object of my invention is to so construct a blower or gas pump of the type described that the impellers may be commercially successfully driven at very much higher speeds than has heretofore been found practicable and to commercially successfully drive such impellers at such increased speeds against higher pressures than have heretofore been found practicable at such high speeds, the construction being such that necessary clearances between the impellers may be substantially decreased.

To this end my invention contemplates the provision of impeller elements of a higher and sufficient flywheel effect (most conveniently obtained by substantially increasing the weight of the impellers which in the higher pressure machines having relatively short impellers would be solid or nearly solid) coordinated with and proportional to the variable torque exerted on the impellers by the gas forces, thus decreasing objectionable torsional angular displacements of the impellers with relation to each other and avoiding torsional reactions of the shafts, thereby preventing breaking of contact of the driving faces of the gear teeth by such reactions; and further by providing gears with teeth which will not impart to the driven gear such fluctuating impulses as will cause the breaking of contacts of the driving faces of the teeth.

By these means I eliminate, or practically eliminate the noise and destructive impacts of the gear teeth and impellers at speeds much higher than has heretofore been found possible, namely at speeds from

2000 to 5000 (and above) feet per minute 65 pitch line velocity, thus making possible the utilization of smaller, and more efficient units at lower cost.

In other words, I have discovered that if the impellers themselves be made sufficiently heavy, so as to give them a very much greater inertia value than they have heretofore possessed, the cyclic distortion of the shafts between the impellers and the gears, particularly in that impeller which is driven through the gears, will be decreased and that consequently a blower in which the impellers themselves have a sufficient inertia value may be driven at speeds very much in excess of present practices, 80 while at the same time the clearances between such impellers may be substantially reduced, and more uniform wear of the gears will be attained.

In order to make the matter clear: One 85 impeller, to the shaft of which the driving power is applied, may be called the driving impeller and the impeller which is rotated through the medium of the gears may be called the driven impeller. When the driven impeller has the tip of one of its lobes in immediate association with the waist of the driving impeller, the pressure on the gear teeth and the resistance to rotation offered by the driven gear, due to the 90 pressure in the pressure side of the system, are at their minimum. As this driven impeller advances, the gear pressure and effective resistance to forward movement of the driven impeller increase and, as this 95 driven impeller is being forwarded by the gear connection, the shaft of the driven impeller, between the impeller and the gear is twisted. When the driven impeller reaches a point where its waist is in association with the tip of the driving impeller, the gear pressure and resistance to forward 100 movement of the driven impeller are at their maximum.

Immediately thereafter the advanced tip 110 of the driven impeller leaves association with the casing and the pressure in the pressure side of the system enters the on-coming delivery pocket between the impeller and the casing, thus causing a sudden pressure 115 equalization, and the resistance to forward movement of the driven impeller decreases until the advancing tip of the driven impeller is in association with the waist of the driving impeller, at which time the gear 120 pressure and resistance to forward movement of the driven impeller have returned to minimum. During this period of decreasing impeller torque, the twist of the shaft of the driven impeller between that impeller and its gear has been correspondingly decreased, such decrease taking effect 125 quite promptly upon the entry of the pres-

sure into the on-coming delivery pocket just mentioned, and the lighter the impeller, the more promptly its shaft twist will be released. The release of this shaft twist causes, or has a tendency to cause, the driven impeller to accelerate because of the energy delivered by the untwisting shaft, and this acceleration causes, or tends to cause, a separation of the driving connection between the gear teeth.

During the above described period of action of the driven impeller and its shaft, a similar action is occurring in the driving impeller and its shaft, but, because of the 15 cycles of the two being spaced ninety degrees apart, the combined effect is to produce twice per revolution an increase of pressure on the few teeth transmitting maximum power to the driven impeller, and a subsequent increased tendency to cause a separation of 20 the driving connection between the gear teeth at the time of minimum transmission of power to the driven impeller.

It will now be recognized that the smaller 25 the inertia value of the impellers, the greater will be the acceleration of the driven impeller as the crest of resistance to forward movement is passed, and that consequently an increase in the inertia value of the impellers will decrease the amplitude of their 30 torsional fluctuations. When this is realized it becomes apparent that, because inertia varies directly as the mass and as the square of the velocity, the necessary inertia value to substantially eliminate objectionable torsional fluctuations of the impellers and produce 35 more uniform gear wear, may be obtained by sufficient increase in mass and speed and that such increase of speed becomes 40 possible because the inertia value of the impeller has been made sufficient to maintain practically uniform angular velocity of the impellers and their proper angular relation to each other.

According to recognized practice prior to 45 my present discovery, blowers of this type with impellers having two hollow lobes have generally been designed with standard shafts and bearings for each gear diameter so that the standard elements, i. e., impellers, shafts, 50 bearings, gear teeth, etc., were capable of transmitting a given normal H. P. per revolution. Also the lengths of the impellers have been made to vary inversely as the pressure against which the blower operates. That is to say, low pressure operation permitted use of axially long impellers and, as desired pressures were greater, these impellers were axially shortened in a manner to maintain approximately the same H. P. per revolution, the same total pressures on impellers, bearings, gears, etc.

Under that practice the shortening of the impellers for high pressure work reduced

their mass and thus reduced their inertia 65 value, whereas, according to my invention, the mass of the shorter impellers, relative to their length, is increased and their inertia value is maintained or increased. Since, according to my present discovery, the 70 shorter impellers for higher pressures are very substantially heavier than heretofore, their inertia value will be sufficient to practically eliminate the objectionable cyclic acceleration of the driven impeller and prevent 75 the breaking of driving contact of the gears, and this in itself permits additional speed which, in turn increases the inertia value of the impellers.

When a sufficient mass is provided, proportionate to the pressure against which the blower is to work, the impellers should, of course, be speeded up, in order to gain the advantage of my invention.

The design should be such therefore, that 85 desired volume and pressure of delivery being known, impeller proportions should be determined on the basis of a large inertia value of the impeller, such inertia value to be a function of speed and mass, the mass to 90 be relatively large and sufficient at the adopted speed to prevent objectionable relative cyclic angular fluctuations of the impellers.

Methods of calculating the variation of 95 angular velocity of masses subjected to fluctuating torque, can be found in engineers' hand books and text books dealing with the design of flywheels for reciprocating steam engines.

There is another distinctly beneficial 100 result attained by the use of high inertia impellers which deserves consideration. Just as each gas forwarding pocket is 105 opened to the delivery, or high pressure, side of the system, there is a sudden increase of pressure in that pocket and this increase of pressure, acting upon the entire side area of the impeller, delivers to the impeller, transversely of its axis and towards the mating impeller, a heavy blow which, if the impeller be light, as has heretofore been the practice, actually displaces the impeller and its shaft sidewise, the extent of this lateral 110 displacement being determined by the looseness of the bearings, the flexibility of the bearing supports and the flexibility of the impellers and shafts. If now, the shorter impellers for higher pressures be made solid or nearly solid, and the longer impellers be 115 made adequately heavy, their increased inertia value is not only effective as a resistance to fluctuations in angular velocity but also has beneficial effect as resistance to the above mentioned lateral displacements caused by the sudden blow of pressure entering the oncoming pocket. This lateral displacement of the impeller and its shaft is

very objectionable, because it makes it almost impossible to maintain tight packing around the shaft where such a structure is used as a gas pump and where leakage 5 around the shaft is objectionable. This lateral deflection of the shaft also produces uneven side wear of the journal bearings thus changing the distance between the gear centers and causing irregular and noisy 10 action of the gears.

The accompanying drawings illustrate my invention. Fig. 1 is a transverse section of a blower or gas pump intended to 15 diagrammatically illustrate the type of structure under consideration; Fig. 2 is a horizontal section through the two impeller shafts and intended to illustrate the invention only diagrammatically; Fig. 3 a fragmentary elevation of two meshing gears 20 having properly flexible teeth for use in connection with my invention, and Fig. 4 a view similar to Fig. 3 showing another form of yielding tooth; Fig. 5 a convenient computation diagram for determining a 25 desirable gear tooth form, and Fig. 6 an adiabatic compression diagram.

In the drawings 10 indicates the casing, 11 and 12 the impeller shafts, 13 and 14 the lobed impellers interdigitated with each 30 other, 15 the inlet, 16 the outlet and 20, 21 the connecting gears.

With the exception of the above described 35 inertia value of the impellers and reduced clearance between the impellers, these elements are of the general form commonly known in the art and the particular contours of the impellers may be considerably varied in accordance with well-known practice. The relatively short impellers, 40 however, are shown as solid because, in the practice of my invention, these impellers must have a very high inertia value and the most convenient way to obtain such high inertia value is to make their lobes solid or 45 nearly solid.

I am aware that liquid pumps of the type 50 under consideration have been made with impellers having solid lobes, but the speed of such pumps was too low to develop the inertia values of the impellers as a function of higher speed of operation.

My invention does not apply to pumps of 55 this type designed for pumping liquids, because operation of such pumps at high speeds becomes destructive to the pump, due to the weight and incompressibility of the liquids.

The increase in compression efficiency by 60 high speed operation of a blower or gas pump of the type under consideration becomes apparent from a study of Fig. 6, which shows the relations of pressures and volumes and the percentage of the discharge 65 stroke required to compress the gases to specified discharge pressures. It will be noted

that the higher the pressure against which the blower is operating, the greater the percentage of the stroke required to produce the necessary compression. In the operation the gas which is being transferred from a lower 70 to a higher pressure is delivered in a succession of small volumes, and where the speed is low the gas at the higher pressure expands backward into the oncoming delivery pocket at an early point in the compression period and the impellers must, therefore, make their advance against the full discharge pressure.

It is evident from a study of these relations that the higher the pressure against 80 which the blower is operating, the higher should be the speed in order to take advantage of the inertia of the gas and accomplish the compression of each discharge volume 85 before the gas in the discharge line has time to overcome its inertia and expand backward into the oncoming discharge pocket. By such action the compression efficiency of the blower at higher pressures is very much increased. Taking, for example a blower 90 operating against 10 lbs. pressure, it will be noted that the mean effective adiabatic pressure when compressing to 10 lbs. is 8.27 lbs. If a slow running blower is working 95 against 10 lbs. pressure, the mean effective pressure against the impellers will at all times closely approximate 10 lbs., but if the blower is so designed and speeded as to accomplish approximately adiabatic compression, the mean effective pressure would 100 only be 8.27 lbs., and a consequent saving in horsepower of 17.3 per cent.

Volumetric efficiency is also greatly increased by high speeds of the impellers. The amount of the slippage of the gas between the impellers themselves and between the impellers and the casing is, of course, dependent upon the length of contact or leakage lines and the amount of clearance between the impellers and between the impellers and casing. For any given pressure the total amount of leakage is a fixed volume in a given time and consequently the volumetric efficiency will be greatly increased by the use of a smaller blower, having 110 shorter leakage lines and smaller clearances. If that smaller blower may be run at a higher speed than has heretofore been found practicable.

I have found that, in connection with providing the impellers of high inertia value, some further advantages may be obtained by providing connecting gears having teeth which are flexible to an extent equal, or 120 substantially equal to the unavoidable departures from theoretical accuracy of the gears existing in tooth form, tooth spacing and mounting.

Another object of my invention is therefore, to combine connecting gears, having 125

suitably flexible teeth, with the high-inertia high-speed impellers.

Where the teeth have been produced by commercially practicable methods there are unavoidable inaccuracies from theoretical perfection and these inaccuracies vary in individual teeth. At the point where two teeth first come into action, the power-delivery tooth is contacted at a point slightly below the pitch line, while the power-receiving tooth is contacted at, or approximately at, the top of the tooth which is, of course, much further beyond the pitch line than is the point of contact below the pitch line on the power-delivery tooth. Bearing in mind the fact that the shapes of the teeth should be such that, when in contact at the pitch line there should be a true rolling contact, it becomes apparent for several reasons that, in order to avoid hammering at the moment of initial contacting of two teeth, the power receiving tooth is the one which at the point of initial contact, should have greater yield than the power-delivery tooth.

For instance, if the power-receiving tooth is incapable of sufficient yield, then one of two things must take place. Either the power-receiving element must, as a whole, be suddenly accelerated, or the power-delivery element must, as a whole, be suddenly retarded. It is apparent, therefore, that the preferable construction, by which individual yield of a tooth may be obtained, should be such that the greatest yield shall take place in the tooth to which the driving force is being applied, and this greatest yield should take place at the time of initial contacting i. e., when the tooth is coming into action.

It is also desirable that whatever of yield there be in each tooth will take place under such conditions as to avoid as much as possible tendencies towards crystallization at any particular section.

The epicycloidal type of tooth, having a radial flank below the pitch line is, of course that type of tooth which in itself is capable of greater yield, but the weakest point of this tooth is at its narrowest cross-section which is at the root, and this type of tooth is therefore incapable, without modification, of satisfactorily providing the yield which is necessary for the practice of my invention, without danger of crystallization and breakage at the root.

Bearing in mind that the tooth may be considered as receiving its load on lines normal to its surface, and that at the time when a load-receiving tooth comes into action the load may be considered as being applied along the line LL, (Fig. 5) the tooth may be analyzed as a beam of uniform flexure (one having a parabolic section) fixed at one end and having its load applied at its outer end T. Applying, then the usual analy-

sis for such a beam loaded at the point T and having, at the root line, a thickness AB equal to the normal root thickness of a normal epicycloidal tooth, it is apparent that that tooth may be given an additional resilience theoretically capable of uniform stress throughout its length by forming a sub-root with sides approximating the parabola sections AC and BD, such sections being portions of the equal stress parabolas intersecting at the point M and passing through the points AB, which define the root thickness of the normal radial flank of the epicycloidal tooth under analysis. It is of course well-known that all portions of a parabola distant from the focus have a tendency to approach a straight line and that, therefore, the theoretical parabola sections AC and BD will in practice be approximately straight. The radial extent of that portion of the tooth defined by the points ABCD may of course be varied, depending upon the metal used, the amount of velocity considered to be necessary, the inertia value of the impellers and various other factors which will readily suggest themselves to a competent designer, and dependent upon circumferential velocities desired, etc., being in all cases sufficient to insure a quiet operation of the gears.

At first glance it might be supposed that the tooth at the points AB would have a weak cross-section, but upon further consideration it becomes apparent that that would not be the case because the parabola MAC or MBD is the uniform stress line and therefore the additional metal in the tooth which lies between the exterior of the tooth and the parabola section MA or MB is simply additional strength or wearing material and there are no lines of weakness at the points A and B.

In order that the method of computation may be understood I give herewith the mathematical analysis for a specific example:

Gear specifications.

Pitch diameter = 26".

Face = 11".

Speed = 400 R. P. M.

No. teeth = 37.

Three teeth to be always in contact.

H. P. to be transmitted = 346.6 H. P.

Velocity pitch line =

$$400 \times 26 \times 3.1416 = 2722.7 \text{ ft. per min.}$$

12

$$\text{Load per tooth} = \frac{347 \times 33000}{2723 \times 3} = 1400\# \text{ (app.)}$$

125

If the load is borne by one tooth

$$P = \frac{1400 \times 3}{11} = 382\# \text{ per 1" face.}$$

Teeth to be epicycloidal radial flank form 130

or involute of sufficient length and shape to permit deflection as desired.

At the point of initial contact at T (Fig. 5) the tooth pressure is exerted along the line of action, cutting the center line of tooth at M. The distance 0.75" is selected as a minimum safe flank-length which will allow proper tooth action without interference, and such a flank-length according to accepted rules of design, requires a root thickness, at AB, of 1.040.

Circular pitch=2.2076.

$$15 \quad \text{Thickness of tooth} = \frac{C.P.}{2} = 1.1038.$$

If a parabolic curve is now generated with the point M as the vertex and the distance Ab as a double ordinate, it will represent a cantilever beam of uniform strength having the load concentrated at M. All of the tooth outside of the parabolic curves will be excess material. If the parabolic curves MXA and MYB are continued as shown on the drawing to C and D, then the portion A-B-C-D will be a portion of uniform strength. In other words, the fiber stresses due to bending in any one section throughout the length of A-B-C-D will be equal to the fiber stresses in any other section.

It should be noted that as a parabolic curve becomes more remote from its vertex it approaches a straight line so that for all practical purposes the sides of the tooth along AC and BD may be made straight.

The mathematical calculations used to find the thickness (d) of the sub-root "A", which is a double ordinate of the parabola, at any place within the portion of uniform strength is as follows.

First calculate the maximum fiber stress $S(AB)$ of the section AB.

$$45 \quad S(AB) = \frac{MC}{I}$$

M=bending moment.

C= $\frac{1}{2}$ thickness of tooth at section under consideration.

I=moment of inertia of tooth at section under consideration.

$$M=382 \times 1.84 = 702.88$$

$$C = \frac{d}{2} = \frac{1.040}{2} = 0.52$$

$$55 \quad I = \frac{bd^3}{12} = 1 \times \frac{1.040^3}{12} = 0.09375$$

$$S(AB) = \frac{703 \times 0.52}{0.09375} = 3900\#$$

60 It should be noted that I have selected the worst condition possible by considering the entire load of 382# per 1" of face to be borne by the one imperfect tooth at its point of initial contact. This gives $S(AB)$ a maximum value.

Now in order to find the thickness (d) at any other distance (L) from the vertex we must keep the maximum fiber stress S constant at 3900# and solve for (d) in the equation—

70

$$S = \frac{MC}{I}$$

$$M = WL \text{ where } W = \text{load per } 1'' \text{ tooth face} = 382\#$$

L=length of beam.

75

$$c = \frac{d}{2}$$

$$I = \frac{bd}{12} b = 1$$

80

$$S = \frac{WL}{d^3} = \frac{6WL}{d^2} \text{ or } d^2 = \frac{6WL}{S}$$

85

$$d^2 = \frac{6 \times 382 \times L}{3900} = 0.588L \quad \text{Equation (I)}$$

By giving L different values we may solve any number of corresponding values for d and thus generate the parabolic curves.

86

The values of d and L however should be such as to give the desired amount of deflection.

Now consider that we desire a deflection of 0.00108 in the tooth taking the tooth as a straight cantilever beam with the load concentrated at the free end (M).

95

$$F = \frac{PL^3}{3EI}$$

100

$$P = 382\#$$

$$E = 15,000,000$$

$$I = \frac{bd^3}{12} b = 1$$

105

then

$$F = \frac{382 \times L^3}{45,000,000 \times \frac{d^3}{12}} = \frac{382 \times 12 \times L^3}{45,000,000 \times d^3}$$

Equation (II) 110

Now from equation (I) $d^2 = 0.588L$.

By combining (I) and (II)

$$F = \frac{12 \times 382 \times L^{3/2}}{45,000,000 \times 0.45} \quad \text{Equation (III)}$$

115

Now since we want a deflection of 0.00108"

$$0.00108 = \frac{12 \times 382 \times L^{3/2}}{45,000,000 \times 0.45}$$

$$L = 2.84$$

$$d = \sqrt{0.588 \times 2.84} = \sqrt{1.67} = 1.292$$

120

It is thus seen that we can find values of (d) and L for any desired deflection.

If the tooth be considered as a cantilever beam of uniform strength and load concentrated at the free end, then

125

$$F = \frac{2 \times PL^3}{3 \times EI^2} = \frac{2PL^3}{3 \times E \times \frac{bd^3}{12}} = \frac{8PL^3}{Ed^3} = 0.00216"$$

130

If the tooth be considered as a cantilever

beam of uniform strength and load acting on the pitch line.

$$F = \frac{8PL^3}{Ed^3} = 0.0005$$

5 It should be noted that in solving for (d) and L any deflection formula may be used. Also the figures and methods which are given are to act as an illustration only, and do not limit the design or construction of 10 the tooth which is essentially a gear tooth having a portion of uniform flexure.

15 This application is filed as a substitute for application No. 101,903, filed by me April 14th, 1926.

15 I claim as my invention:

20 1. A blower comprising a casing, two interdigitated lobed impellers mounted within the casing, and a pair of meshing gears 25 rotatively connecting said impellers, the said gears having teeth capable of circumferential yield under the applied load of approximately the unavoided departure of the contacting surfaces of said teeth from theoretical accuracy.

25 2. A high speed blower comprising a casing, two interdigitated lobed impellers mounted within the casing and having an inertia value which is high relative to their gas load torque variations, and a pair of 30 meshing metal gears rotatively connecting said impellers, the said gears having teeth capable of circumferential yield under applied load of approximately the unavoided 35 departure of the contacting surfaces of said teeth from theoretical accuracy, whereby the tendency of tooth wear is toward uniformity throughout the circumferences of the gears.

40 3. A blower comprising a casing, two interdigitated lobed impellers mounted within the casing and a pair of meshing gears 45 rotatively connecting said impellers, the said gears having teeth capable of circumferential yield under applied load of approximately the unavoided departure of the wearing surfaces of said teeth from theoretical accuracy, each of said teeth having a sub-root of approximately uniform flexure.

50 4. A high speed blower comprising a casing, two interdigitated lobed impellers mounted within the casing and having an inertia value which is high relative to their gas load torque variations, and a pair of 55 meshing metal gears rotatively connecting said impellers, the said gears having teeth having a sub-root of approximately uniform flexure and capable of circumferential yield under applied load of approximately the unavoided departure of the wearing surfaces

of said teeth from theoretical accuracy, whereby the tendency of tooth wear is toward uniformity throughout the circumferences of the gears. 60

5 A high speed blower comprising a casing, two interdigitated lobed impellers mounted within the casing, and a pair of meshing metal gears rotatively connecting the said impellers and having teeth of a form providing at least two pairs of teeth in mesh at all times and capable of circumferential yield at the contacts, the inertia value of 70 said impellers being relatively high, whereby the tendency of tooth wear is toward uniformity throughout the circumference of the gears. 75

6 A high speed blower characterized by 80 a casing, two interdigitated lobed impellers rotatably mounted within and coacting with the casing, and a pair of meshing gears rotatively connecting said impellers, the said impellers having an inertia value which is sufficient to maintain continuous contact of the working faces of the gear teeth at high speeds and which is high relative to their gas load torque variation, whereby they may 85 be rotated at high speed with small clearance. 85

7 A high speed blower characterized by 90 a casing, two interdigitated lobed impellers rotatably mounted within and co-acting with the casing, a pair of meshing gears 95 rotatively connecting said impellers, said impellers having such great mass as is adequate, at the intended high speed of rotation, to develop inertia value which is sufficiently high relative to the cyclic gas load torque fluctuation to maintain continuous contact of the working faces of the gear teeth at such speeds, whereby small clearance between the impellers may be employed and efficient, normal, high-pressure, high-speed operation assured. 100

8 A high speed blower comprising a casing, two interdigitated lobed impellers mounted within the casing, and a pair of gears rotatively connecting said impellers and having teeth of a form providing at 105 least two pairs of teeth in mesh at all times, the inertia value of said impellers being high relative to their gas load torque variations, whereby the tendency of tooth wear is toward uniformity throughout the circumference of the gears. 110

In testimony whereof, I have hereunto set my hand at Connersville, Indiana, this 24th day of February, A. D. one thousand nine hundred and twenty-seven.

JOHN T. WILKIN.
